UNITED STATES PATENT OFFICE.

WILLIAM W. URQUHART, JOSEPH LINDSAY, AND ROBERT ALLAN, OF DUNDEE, COUNTY OF FORFAR, SCOTLAND.

COP-WINDING MACHINERY.

SPECIFICATION forming part of Letters Patent No. 242,718, dated June 7, 1881.

Application filed October 21, 1880. (No model.) Patented in England January 22, 1879.

To all whom it may concern:

Be it known that we, WILLIAM WALTON URQUHART, JOSEPH LINDSAY, and ROBERT ALLAN, subjects of the Queen of Great Britain and Ireland, all residing at Dundee, in the county of Forfar, Scotland, have invented a certain Improvement in Cop-Winding Machinery, (for which we obtained a patent in Great Britain, No. 264, dated 22d January, 1879,) of which the following is a specification.

In our improved machinery the winding-spindles are short and have no movement in the direction of their length, either while winding or when the cops are being removed. The ordinary conical forming-cups are employed to give the required compactness or firmness to the cop as it is being wound, the degree of firmness or hardness being regulated by pressure applied endwise to the cop, or downward when the cops are wound in a vertical position, the cops receding or rising from the cups against the pressure, as they are gradually formed by the winding operation. Each cup is a separate loose piece, being held by means of trunnions formed on it, so that it can adjust itself to act equally on all sides of the cop, and the part carrying it is movable by means of a handle. The winding-spindles are driven by means of ordinary bevel-wheels, and each has an improved clutch fitted with renewable engaging-pins, of steel. The shortness of the winding-spindles is a special and advantageous feature of our improved machinery. Each spindle projects only a short distance through the cup, the part of the spindle on which the yarn is wound being made with three or more flat sides and slightly tapered, with the point rounded, and as the cop grows upward or from the cup, in consequence of the winding action continually adding conical layers of yarn to the lower end within the cup, the upper part of the cop gradually leaves the spindle, and when the desired length of cop has been formed the spindle end projects only into the conical end of it, and the cop can consequently be removed with extreme facility. The upper or outer end of the cop is pressed upon and steadied by a small center or ball, arranged to move in a line coincident with the axis of the winding-spindle. The part holding the outer center or ball

acts on an adjustable stop or rod, through which, when the desired length of cop is formed, the clutch-lever is released, and, being weighted, disengages the clutch and stops the winding action. The clutch-lever is also released by means of a detector-lever when the yarn breaks or fails.

In the accompanying drawings, Figure 1 is a transverse vertical section of a cop-winding machine made with our improvements, and having a row of vertical spindles along each side of it. Fig. 2 is a front elevation, showing the parts appertaining to one spindle. Figs. 3 and 4 are a plan and a side elevation of the ball-lever, or part having the upper or outer center or ball. Figs. 5, 6, and 7 are a plan, an end elevation, and a side elevation of the cup holder or lever. Figs. 8 and 9 are a front elevation and a side elevation of the stop-rod. Figs. 10 and 11 are a plan and a front elevation of the cup. Figs. 12, 13, and 14 are a plan, a side elevation, and a front elevation of the detector-lever. Figs. 15 and 16 are a plan and a side elevation of a catch-lever connected with the clutch details. Figs. 17 and 18 are a plan and a side elevation of the clutch-lever, and Figs. 19 and 20 are a sectional plan and a side elevation, showing the clutch.

The main framing of the machine consists of transverse vertical frames or standards 21, placed at the ends and at intermediate points, and connected by four horizontal rails, an upper one, 22, and a lower one, 23, extending along each side. Most of the details appertaining to each spindle are carried upon or fitted in connection with a vertical frame-plate, 24, (seen best in Fig. 2,) bolted to the upper and lower rails, 22 23, each such frame-plate 24 being made with a long slot, 25, in which the ball-lever 26 and the cup-lever 27 work, and with short slots 28 29 for the fulcrum ends of the ball and cup levers of the opposite side, the corresponding frame-plate, 24, on the opposite side having similar slots for the fulcrum ends of the ball-lever 26 and cup-lever 27 of the side that is being described. Each winding-spindle 30 is short and has no movement in the direction of its length, being held in upper and lower bearings, 31 32, formed on the frame-plate 24. An ordinary conical forming-

cup, 33, is employed to give the required compactness or firmness to the cop as it is being formed; but this cup is loose, being formed with trunnions, which rest in notches 34 in 5 the forked cup-lever 27, so that it can adjust itself to the cop and equalize the pressure on all sides. The cup - lever 27, which has one side of its forked part extended to form a handle, 35, is passed through the slot 25 in 10 the frame-plate 24 and extends across the machine to a slot, 29, in the frame-plate at the other side, the bottom of the latter slot serving as a fulcrum to the lever. A stud or small projection, 36, is formed on one side of the cup- 15 lever 27, and, bearing against the face of the frame-plate 24, prevents the lever from being pushed too far inward through the slot 25; and the cup-lever 27 is also formed with an upwardly-projecting part, 37, which serves as a 20 rest for the ball - lever 26 when in its lowest position.

The row of winding-spindles 30 at each side of the machine is directly over a horizontal driving-shaft, 38, having on it bevel-wheels 39, which gear each with a bevel-pinion, 40, loose on the lower end of a winding-spindle, 30, the pinion driving the spindle through a special clutch, hereinafter described. It is one advantage of our improved arrangement that the bevel wheels 39 and pinions 40 do not require to be of the skewed kind, as the spindles 30 have no vertical or endwise movement and can be placed in the plane of the driving-shaft. The feature is not absolutely novel in itself, but we are enabled to adopt it without inconveniences experienced with other arrangements. One part of the clutch is a renewable pin, 41, which is fixed by a pinching-screw in a boss formed for it on the bevel-pinion 40, a similar boss being formed at a diametrically-opposite point to preserve the balance. The other part of the clutch is a two-collared tube, 42, fitted to slide on the spindle 30, but engaging with it by a pin and groove, and provided with a renewable pin, 43, which is fixed by a pinching-screw, and which engages with the pin 41 of the bevel-pinion 40 when the tube is moved near to the pinion. The clutch 42 is moved by a forked lever, 44, the prongs of which enter between the collars of the clutch, and this clutch-lever 44 has jointed to its other end a bar, 45, which extends down vertically and is jointed to a treadle or foot-lever, 46, below. The parts are made of such weights that they raise the clutch 42 out of gear when the clutch-lever 44 is not held by means of a catch-projection, 47, formed on one side of it. When, by action on the treadle 46, the inner end of the clutch-lever 44 is raised its catch-projection 47 engages with a latch-catch, 48, formed on a catch-lever, 49, centered on a backwardly-projecting part, 50, of the frame-plate 24, this catch-lever 49 having the weights of its parts so proportioned that the catch 48 enters under the catch 47 of the clutch-lever when this rises high enough. A shoulder formed on the bar

45 prevents it from being raised too high by encountering the bottom rail, 23.

Each spindle 30 extends upward only to about the top of the cup 33, and the part within the cup is made with flat sides and slightly tapered, the point or upper end being rounded. When the cop is completed the spindle end projects only into the conical part of it, and the cop can be very easily lifted off the spindle by raising the cup-lever 27 by means of its handle 35. The upper end of the cop is pressed upon and steadied by a small center or ball, 51, arranged to move in a line coincident with the continued axis of the winding-spindle 30. This ball 51 is formed on a downwardly-projecting part of the front end of the ball-lever 26, which lever works in the slot 25 of the framing-plate 24, its other end being entered into a slot like the slot 28, but in the frame-plate 24 at the other side of the machine.

On one side of the ball-lever 26 there are formed two studs, 52, which guide the lever by sliding one on the outside and the other on the inside of the frame-plate 24, at one edge of the slot 25, this slot having a widened part at its top to allow of the entrance of the innermost of the two studs 52. A curved rib, 53, (seen at the right-hand side of Fig. 1,) is formed at the back of the frame-plate 24, at the part where the innermost stud, 52, moves, and the curvature of this rib 53 is such as to cause the ball 51 to move with sufficient accuracy in a line coincident with the continued axis of the winding-spindle. On the other side of the ball-lever 26 there is centered a handle-catch, 54, which can engage with any one of a series of ratchet-teeth, 55, formed on the frame-plate 24, along one side of the slot 25, and this catch serves for supporting the ball-lever 26 in any of its positions, being held clear of the ratchet-teeth by hand when lowering the lever. The ball-lever 26 may be made of sufficient weight for pressing the cop into the cup 33, or a weight may be applied to it for that purpose.

When the desired length of cop has been formed the ball-lever 26, in rising, encounters a clamp or stop, 56, on the stop-rod 57, this rod ordinarily resting by a hook formed on its upper end, which passes through a slot in the top rail, 22. The stop 56 can be clamped in different positions on the rod 57, so as to be reached later or sooner by the ball-lever 26, accordingly as a longer or shorter cop is desired. The numerals shown on the bar 57, in Fig. 8, represent lengths of cop in inches. The rod 57 extends downward past the catch-lever 49, and it has formed on its inner edge a shoulder or incline, 58, which, when the rod is lifted by the ball-lever 26, acts on a cranked arm, 59, formed on the catch-lever 49, and makes that lever let go the clutch-lever 44, which thereupon disengages the clutch and stops the winding action. 115 120 125

The yarn may be drawn off either reels or 130 bobbins, but is shown as being drawn off bobbins 60, to which a drag is applied by means

of a weighted spring-lever blade, 61, of thin metal, which bears on the yarn itself on the bobbin, its action on full and empty bobbins being in consequence more uniform than when pressure is applied to the bobbin. From the bobbin 60 the yarn passes to a pulley or guide, 62, on the outer end of a light detector-lever, 63, and thence to the finger of the traverse-guide lever 64, which finger works close to the slot in the side of the cup 33 in the usual way. The detector-lever 63 consists of a stout wire fixed in a peculiar boss or center, 65, Figs. 12, 13, 14, centered on a horizontal pin. This boss 65 is formed with one toe, 66, which bears against a blade-spring, 67, fixed to the frame-plate 24, and with a second toe, 68, which extends under an arm, 69, formed on the catch-lever 49. The strain of the yarn holds up the lever 63, and the spring 67 tends to equalize the tension; but when the yarn breaks or fails the lever 63 falls, and its toe 68 then trips the catch-lever 49, and thereby causes the disengagement of the clutch and the stoppage of the winding action.

The traverse-guide levers 64 are adjustably fixed on horizontal shafts 70, which shafts are made to rock by mechanism of the kind usually applied for that purpose. Each guide-lever 64 is a stout wire fixed in one of a pair of half-bosses, 71, bolted together on the shaft. The shaft 70 is plain throughout, and the bosses 71 can be set in any position along it, and also in any position round it, so that each lever 64 can be independently adjusted with accuracy to suit the spindle 30 and cup 33, in connection with which it works.

We claim as our invention in cop-winding machines—

1. The mode herein described of winding cops—that is, winding the cop, and as it is being wound causing it to gradually recede from its spindle, substantially as set forth.

2. In a winding-machine, the combination of driving mechanism and a winding-spindle with a forming-cup and a yielding center or ball, adapted to press on the wound end of the cop as it recedes from the spindle during the winding operation, all substantially as described.

3. In a cop-winding machine, the combination of driving mechanism and a winding-spindle with a stationary forming-cup, 33, and a pivoted lever, 27, having a ball, 51, adapted to rest on the end of the cop as the latter is being wound.

4. The combination of cop-winding mechanism with a cup-carrier, 27, and a cup, 33, pivoted thereon, substantially as specified.

5. The combination of slotted frames and guide-rib 53 with a ball-lever, 26, supported in one of said frames and adapted to a guide-slot in the other, and provided with guide-studs 52, all substantially as and for the purposes set forth.

6. The combination of driving mechanism, 65 winding-spindle, forming-cup, and ball-lever 26 with a stop-rod, 57, catch-lever 49, having an arm, 59, and a clutch-lever and clutch, all substantially as described.

7. The combination of winding mechanism and winding-spindle, and pivoted detector-lever 63, having a toe, 68, with catch-lever 49, having an arm, 69, and catch 48, and with the clutch-lever 44, and clutch, all substantially as set forth.

In testimony whereof we have signed our names to this specification in the presence of two subscribing witnesses.
